Primary Examiner — Rosemary K Tarcza*Assistant Examiner* — Christy M Nemeth(74) *Attorney, Agent, or Firm* — Meagher Emanuel Laks Goldberg & Liao, LLP(57) **CLAIM**

We claim the ornamental design for a wireless charging pad, as shown and described.

DESCRIPTION

FIG. 1 is a top right perspective view of a wireless charging pad showing our new design;

FIG. 2 is a top view of the wireless charging pad of FIG. 1; FIG. 3 is a bottom view of the wireless charging pad of FIG. 1;

FIG. 4 is a left side view of the wireless charging pad of FIG. 1;

FIG. 5 is a right side view of the wireless charging pad of FIG. 1;

FIG. 6 is a front view of the wireless charging pad of FIG. 1; and,

FIG. 7 is a rear view of the wireless charging pad of FIG. 1. The broken lines in the figures represent portions of the article which form no part of the claim.
